CLAIM

The ornamental design for a heat press machine, as shown and described.

DESCRIPTION

FIG. 1 is a front, top and left side perspective view of a heat press machine, showing our new design;

FIG. 2 is a front, top and left side perspective view thereof, shown in a state of use;

FIG. 3 is a rear, bottom and right side perspective view thereof;

FIG. 4 is a front view thereof;

FIG. 5 is a rear view thereof;

FIG. 6 is a left side view thereof;

FIG. 7 is a right side view thereof;

FIG. 8 is a top plan view thereof; and,

FIG. 9 is a bottom plan view thereof;

The broken lines shown in the drawings illustrate portions of the heat press machine that form no part of the claimed design.
